UNITED STATES PATENT OFFICE.

ANDREW JENSEN, OF KENOSHA, WISCONSIN.

SPRING-COILING MACHINE.

1,250,584.

Specification of Letters Patent. Patented Dec. 18, 1917.

Application filed January 6, 1917. Serial No. 140,885.

To all whom it may concern:

Be it known that I, ANDREW JENSEN, a citizen of the United States, residing at Kenosha, county of Kenosha, and State of Wisconsin, have invented certain new and useful Improvements in Spring-Coiling Machines, of which the following is a specification.

This invention relates to improvements in spring coiling machines of the kind typically illustrated in Letters Patent to Hoefer, No. 598,094, dated Feb. 1, 1898. Spring coiling machines of this type employ a pair of wire-feed rolls, wire guides on both sides of the feed rolls, a coiler by which a uniform or variable bend is imparted to the wire, a spreader or spacer by which the coils of the spring are separated to the desired or required extent, and a cutter usually located between the coiler and the spreader. The feed-rolls, guides, and coiler are arranged in alinement; and, while the spreader is movable to vary the spacing of the coils, the extreme free ends of the spring, as delivered by the machine, do not lie within or inwardly of the planes of the approximately flat end coils but project outwardly thereof. For many purposes for which coil springs are used, such as furniture upholstery, it is necessary to flatten the end coils by bending the free ends of the spring either within or inwardly of the planes of said end coils. Heretofore this has involved a subsequent, separate and distinct operation by hand, and, in consequence, has entailed an additional labor and expense in the manufacture of these springs.

The primary object of the present invention is to provide an improvement in the spring-coiling machine itself whereby this flattening of the end coils and inward tucking of the free ends of the wire of the spring may be effected simultaneously with the forming of the spring, and without necessitating any subsequent operation on the spring. In the embodiment of the invention herein presented this is accomplished by means of a special form and relative location of the wire guide that is located between the feed-rolls and the coiler, and commonly known as the forming plug.

In order that my invention, its principle of operation, and its attendant advantages may be readily understood by those skilled in this art, I have illustrated one practical

and workable embodiment thereof in the accompanying drawings, in which—

Figure 1 is a front elevation of a spring coiling machine embodying my improvement;

Fig. 2 is a horizontal section through the wire-engaging parts of the machine, on the line 2—2 of Fig. 1;

Fig. 3 is a detail perspective elevation of the forming plug;

Fig. 4 is a side elevation of a spring as made by machines now in use;

Fig. 5 is a side elevation of the same spring when made with a machine equipped with my improvement.

Referring to the drawings, 6 designates generally the front portion of the machine frame on which the several principal operating parts of the machine are mounted. 7 designates a stationary wire guide that conducts the wire into the nip of a pair of upper and lower feed-rolls 8 and 9, respectively. The upper feed-roll 8 is so mounted as to be capable of a separating movement from the roll 9 so as to intermit the feed between successive springs in order to permit the proper operation of the wire cutter, all as well understood in machines of this type. Beyond the feed-rolls 8 and 9 is the coiler consisting, as herein shown, of a peripherally grooved roller 10 that is mounted on the lower end of a depending arm 11 in turn carried by a rock shaft 12 that is actuated through the connections clearly shown in Fig. 1 by a cam 13. Just below the coiler 10 is the cutter comprising the stationary blade 14 and the endwise reciprocating blade 15 coöperating therewith. Between the cutter and the lower feed-roll is located the reciprocating spreader bar 16, by which the successive coils are spread apart or spaced as they are produced, the working face of the spreader bar being beveled, as usual in these machines, in order to give to the wire as it slides over the same an outward bend in a direction away from the front of the machine.

Between the feed-rolls and the coiler is located another wire guide commonly known as the forming plug. In most machines of this type as at present constructed this forming plug comprises a stem or shank that is removably mounted in a hole in the frame by means of a setscrew and a head on the outer or forward end of the stem 110

that is provided with either a hole extending diametrically therethrough for the passage of the wire, or a pair of laterally offset guide-rolls on its forward face between which the wire passes to the coiler. In the present practice the feed-rolls, the coiler, and the wire-engaging portion of the forming plug are all located in alinement with each other, and the spreading or spacing of the coils is effected wholly by the spreader. As a result of this old construction, a spring such as is illustrated in Fig. 4 is produced, wherein it will be noted that the terminal portions A of the wire project beyond or outwardly of the general transverse plane of the end coils. In other words, the spring lacks the substantially flat end coils which it must have before it is adapted for many of its intended uses; and a subsequent operation to bend the projecting ends A inwardly of the spring is required.

I have discovered that by means of a comparatively simple change in the relative locations of the wire-guiding passage of the forming plug and the coiler, I can produce a peculiar effect in the wire which, when the latter is cut between successive springs, causes the free ends of the wire to spring inwardly of the end coils of the spring, remaining permanently in such position. Referring principally to Figs. 2 and 3, 17 designates the stem or shank of my improved forming plug, and 18 designates the head thereof. Extending diametrically through the head 18 is the usual guiding hole or passage 19, and it will be observed by reference to Fig. 2 that the forming plug, the stem of which may be adjustably secured in place by a setscrew, indicated at 20, is so positioned that the wire-guiding hole or passage 19 thereof is offset to a slight extent inwardly of the vertical plane of the coiler 10, so that the wire passes from the exit end of the guide passage 19 to the groove of the coiler 10 at a slight angle to the axis of the passage 19. By reason of this relative off-setting of the coiler to the guide passage in the forming plug, said coiler in its operation tends to twist the wire about its longitudinal axis, thereby setting up in the wire a torsional strain, as a result of which, when the wire is severed by the cutter, the two ends thus formed spring laterally away from each other, the rear or last-formed end of the spring springing inwardly of the last formed coil as indicated at B in Fig. 5, and the foremost or first formed end of the spring similarly springing inwardly of the first formed coil, as indicated at B' in Fig. 5. For the attainment of this result it is immaterial whether the nip of the feed rolls 8 and 9 be in alinement with the groove of the coiler 10, as herein shown, or in alinement with the guide passage 19 of the forming plug, or with neither; but since, in ex-

isting machines, the feed rolls and coiler are in alinement with each other, the simplest and most practical embodiment and application of the invention lies in so setting the forming plug that its wire-guiding aperture 19 is slightly offset laterally relatively to a straight line connecting the nip of the feed rolls and the groove of the coiler, and I have found experimentally that in this arrangement a lesser amount of relative offset of guide passage and coiler is required than where the guide passage is in alinement with the nip of the feed rolls. It should be understood, however, that the relative lateral offsetting of the coiler and the guide passage of the forming plug is the only thing essential to the production of the novel result of the automatic insetting of the ends of the spring hereinabove described and shown in Fig. 5.

I have found, however, that where the advance end of the spring is given this peculiar in-set by the means and in the manner just described, it will, as the formation of the spring proceeds in the machine herein illustrated, strike the stationary blade 14 of the cutter unless means be provided to guide it past the cutter blade. Any suitable deflecting means may be employed for this purpose within the purview of the present invention, but a simple and practical means for this purpose consists of an inclined or cam surface 21 on that side of the face of the forming plug which lies nearest the cutter. As the advance end of the wire sweeps past the beveled face of the spreader it next engages a beveled portion 22 (Fig. 3) on the lower side of the face of the plug that is flush with the beveled face of the spreader when the latter is fully retracted, and as the wire end sweeps across the face of the forming plug it is deflected outwardly by the protuberant inclined surface 21 sufficiently to cause the end to safely clear the stationary blade of the cutter. By reference to Fig. 1 it will be observed that the base line of the inclined surface 21 lies at substantially a right angle to the wire-guiding hole 19. This temporary outward deflection of the advance end of the coil, however, does not affect the permanent inward set which the wire receives in passing through the laterally offset forming plug, and the advance end springs back inwardly of the foremost coil as soon as the latter has been formed by the machine.

By more or less offsetting the forming plug relatively to the coiler, the extent of inward deflection of the terminal portions of the spring may be regulated as desired.

From the foregoing it will be manifest that the purpose or function of the protuberant inclined surface 21 on the face of the forming plug is simply to prevent collision of the advance end of the wire with

the stationary blade of the cutter. Other wire-deflecting means may, obviously, be employed for this purpose; but the simplest and most practical location for this member 5 is on the forming plug itself, as herein shown and described.

It is believed that the mode of operation and advantages of the invention will be readily understood by those familiar with 10 the operation of spring coiling machines without further description; and hence, without limiting myself to the precise details herein shown and described,

I claim:

15 1. In a spring coiling machine, the combination with a forming plug having a transverse wire guide, of an oscillating coiler the wire-engaging portion of which is laterally offset relatively to said wire guide.

20 2. In a spring coiling machine, the combination with a forming plug having a transverse wire-guiding aperture, of an oscillating coiler the wire engaging portion of which is laterally offset on the delivery side 25 of the machine relatively to said wire-guiding aperture.

30 3. In a spring coiling machine, the combination with feed-rolls and a coiler, of a forming plug having a wire guide that is laterally offset relatively to a straight line between the nip of the feed-rolls and the wire-engaging portion of the coiler.

35 4. In a spring coiling machine, the combination with feed-rolls and a coiler located in a common plane, of a forming plug having a wire guide that is laterally offset relatively to said plane on the side opposite that on which the spring is delivered.

5. In a spring coiling machine, the combination with feed-rolls and a coiler located 40 in a common vertical plane, of a cutter below said coiler, a forming plug having a wire guide that is laterally offset relatively to said plane on the side opposite that on which the spring is delivered, and a deflector for 45 the advance free end of the first-formed of the spring serving to prevent collision of said free end with said cutter.

6. In a spring coiling machine, the combination with feed-rolls and a coiler located 50 in a common vertical plane, of a cutter below said coiler, a forming plug having a wire guide that is laterally offset relatively to said plane on the side opposite that on which the spring is delivered, and a deflector 55 for the advance free end of the first-formed coil of the spring carried by said forming plug and serving to prevent collision of said free end with said cutter.

7. A forming plug for spring coiling machines, having a transverse wire-guiding aperture, and a protuberance on one end thereof formed with an inclined surface, the base line of which lies at substantially a 60 right angle to said aperture. 65

8. A forming plug for spring coiling machines, comprising a stem, a head having a transverse wire-guiding aperture, and a protuberance on the face of said head formed with an inclined surface, the base line of 70 which lies at substantially a right angle to said aperture, said inclined surface serving to laterally deflect the free end of a coil passing over said face.

ANDREW JENSEN.
